(57) **CLAIM**

The ornamental design for an area light, as shown and described.

DESCRIPTION

FIG. 1 is a top, front perspective view of an area light showing our new design.

FIG. 2 is a front view of an area light;

FIG. 3 is a rear view of an area light;

FIG. 4 is a left side view of an area light;

FIG. 5 is a right side view of an area light;

FIG. 6 is a top view of an area light;

FIG. 7 is a bottom view of an area light; and,

FIG. 8 is a bottom, rear perspective view of an area light. Any shading and cross-hatching are not features of the design but are utilized to illustrate the surface contours of the area light design in the drawings.

1 Claim, 8 Drawing Sheets
